TRUSS CONNECTOR PLATE

Donald L. Thomas, 615 Melinda Drive,
Oxford, Ohio 45056

Filed Oct. 2, 1969, Ser. No. 19,378

Term of patent 14 years

Int. Cl. D8—04

U.S. Cl. D8—266

Fig. 1.

Fig. 4.

Fig. 2

Fig. 5.

Fig. 3.

Fig. 6.

Fig. 7.**Fig. 8.****Fig. 9.**

FIG. 1 is a top plan view of a truss connector plate according to my new design.

FIG. 2 is an elevational view thereof.

FIG. 3 is a bottom plan view thereof.

FIG. 4 is a top plan view of a first modified form thereof.

FIG. 5 is an elevational view of the first modification.

FIG. 6 is a bottom plan view of the first modification.

FIG. 7 is a top plan view of a second modification of my new design.

FIG. 8 is an elevational view of the second modification.

FIG. 9 is a bottom plan view of the second modification.

I claim:

The ornamental design for a truss connector plate, as shown and described.
